UNITED STATES PATENT OFFICE

95,191

DESIGN FOR A BRACELET CHAIN

Albert E. R. Speidel, Providence, R. I., assignor to Speidel Corporation, Providence, R. I., a corporation of Rhode Island

Application May 29, 1934, Serial No. 51,950

Term of patent 3½ years

To all whom it may concern:

Be it known, that I, Albert E. R. Speidel, a citizen of the United States, residing at Providence, in the county of Providence and State of Rhode Island, have invented a new, original, and ornamental Design for Bracelet Chain, of which the following is a specification, reference being had to the accompanying drawing, forming part thereof.

Fig. 1 is a top plan view of a bracelet chain showing my design which consists of a plurality of comparatively large links interconnected by a smaller central link, and,

Fig. 2 is an enlarged perspective view of one of the connecting links shown in Fig. 1 which constitutes the dominant feature of the design.

What I claim is:—

The ornamental design for a bracelet chain, substantially as shown and described.

In testimony whereof I have affixed my signature.

ALBERT E. R. SPEIDEL.
